12 Claims. (Cl. 321—16)

1

This invention relates to control apparatus for alternating current electrical generating systems and, more particularly, to improved control apparatus for alternating current generating systems of the type used on motor vehicles for battery charging and other auxiliary purposes and in which the speed of the alternator varies with the speed of the vehicle driving motor.

In the higher voltage battery charging systems, such as for charging storage batteries of twelve to sixteen cells or more, a troublesome problem has always been present in regard to obtaining a long operating life for the voltage regulators of the relay or vibratory contact type used with such higher voltage systems. The problem encountered results from the greater amount of energy required to be controlled by the vibratory contacts of the voltage regulator. These higher voltage systems usually require the use of a high value of control resistance in parallel with the contacts of the regulator and this increases the arc intensity at the contacts and, hence, increases the destructive effect on the contacts.

In the case of voltage regulators of the double contact type used with such higher voltage battery systems, another problem is encountered due to ionization of the gas present between the contacts during transfer of the operating point of the regulator from one pair of contacts to the other. Thus in a situation where the voltage regulator is vibrating on the upper pair of contacts to control the voltage of the generator while the latter is operating under heavy load and at medium speeds and the load is dropped suddenly, the regulator thereupon transfers its operating point to the lower pair of contacts and continues to maintain the voltage of the generator at its normal value. If, at the time of this transfer of the operating point of the voltage regulator from one pair of contacts to the other, an arc occurs between the upper pair of contacts and maintains an ionized path therebetween until the lower pair of contacts is closed, a short circuit will occur through such ionized path which may have a destructive effect on the contacts even to the extent of causing the contacts to be welded together into a solid mass.

The present invention minimizes or eliminates these difficulties and, as its principal object, provides generator system control means in which the contacts of the voltage regulator, whether single or multiple pairs of contacts and regardless of the voltage of the system, are required to control only a relatively small amount of elec-

2

trical energy which will not be injurious to the contacts, and in which such a relatively small amount of energy acting through a saturable reactor included in the field excitation means of an alternator produces a strong regulating action on the alternator.

Another object of the present invention is to provide improved control apparatus for a generating system in which the excitation means for the alternator field includes an auxiliary rectifier and a saturable reactor, and in which the magnetizing or control coil means of the reactor is controlled by regulator means of the relay type which is automatically responsive to the operating condition of the alternator and in effect acts as a voltage sensing device.

Still another object is to provide improved generator control apparatus of the character mentioned in which the regulator means consists of both voltage and current regulators of the relay type.

A further object is to provide improved generator control apparatus of the kind above referred to in which the field excitation means for the alternator includes impedance coil means of the reactor and which impedance coil means is located in the alternating current portion of the field circuit.

Yet another object is to provide improved generator control apparatus of the character above indicated in which the alternator is a three-phase alternator and the field excitation means for the alternator includes a three-phase rectifier and a saturable reactor for each of the three-phase alternating current portions of the field circuit.

As an additional object this invention provides control apparatus of the character mentioned in which the field excitation means for the alternator includes a saturable reactor controlled by a voltage regulator of the relay type responsive to the operating condition of the alternator, and in which the energization of the magnet coil means of the voltage regulator is controlled by a voltage divider.

This invention can be further briefly summarized as consisting in certain novel combinations and arrangements of parts hereinafter described in detail and particularly set out in the claims hereof.

In the accompanying sheets of drawings, Fig. 1 is a wiring diagram showing generating system control apparatus embodying the present invention and in which a saturable reactor located in the alternating current portion

3

of the field circuit of an alternator is controlled by regulator means of the relay type responsive to the operating condition of the alternator.

Fig. 2 is a wiring diagram showing a generating system similar to that of Fig. 1 but in which the voltage regulator of the regulator means is of the double contact type; and

Figs. 3 and 4 are wiring diagrams showing generating systems similar to the generating systems of Figs. 1 and 2 respectively, but in which the saturable reactor of the field excitation means is a three-phase saturable reactor.

In the embodiment of the invention illustrated in Fig. 1, a generating system 10 is shown comprising an alternator 11 which delivers current through a main or power rectifier 12 to an external direct current load here represented by a storage battery 13 to be charged. The alternator 11 may be of the inductor type and is here shown as a three-phase alternator having star-connected inductor windings 14a, 14b and 14c and a field winding 15. The main rectifier 12 is a full wave three-phase bridge type rectifier which can be of the dry plate construction and comprises circuit arms 12a, 12b and 12c with which the respective inductor windings 14a, 14b and 14c are connected by conductors extending from the alternating current load terminals 16a, 16b and 16c of the alternator. The rectifier 12 has direct current load terminals 17a and 17b to which the storage battery 13, representing the external load, is connected by the direct current load conductors 18a and 18b.

The external direct current load circuit represented by the conductors 18a and 18b is controlled by a load relay 20 which, in accordance with one feature of the present invention, has a novel energizing circuit which will be presently described. This load relay may be of the type comprising a magnet frame 21 including a core 22 carrying a magnet coil 23 and a movable armature 24 in cooperating relation to such frame and core. The load relay 20 also includes normally open stationary and movable switch contacts 25 and 26 in series relation to the load conductor 18b of the external direct current load circuit.

The magnet windings 23 of the load relay 20 is adapted to be energized from the alternator 11 through an auxiliary rectifier 27 which is here shown as being a three-phase full wave bridge type rectifier having circuit arms 27a, 27b and 27c and a pair of direct current load terminals 28 and 29. The terminals of the magnet coil 23 are connected with the direct current terminals 28 and 29 by the conductors 30 and 31. The circuit arms 27a, 27b and 27c of the auxiliary rectifier 27 are connected respectively with the terminals 16a, 16b and 16c of the alternator 11 by the conductors 32, 33 and 34.

As an important feature of the present invention the improved generating system 10 includes regulating means which is automatically responsive to the operating condition of the alternator 11 and varies the excitation of the alternator field 15 so as to maintain the terminal voltage of the alternator substantially constant regardless of wide variations occurring in the speed at which the alternator is driven and in the value of the load imposed thereon. This regulating means comprises a voltage regulating unit 35 of the vibratory contact electromagnetic relay type and a current regulating unit or load limitor 36 which is also of the vibratory contact electromagnetic relay type. The field excitation means

4

for the alternator 11 includes a field circuit having therein an auxiliary rectifier 37 and a saturable core reactor 38 with which the regulator means cooperates for controlling the field excitation.

The field energizing circuit for the alternator 11 comprises a direct current portion which includes the field winding 15 and a pair of conductors 15a and 15b connecting the ends of the field winding with the direct current terminals 40 and 41 of the field rectifier 37. The field circuit also comprises an alternating current portion connecting the alternating current terminals 42 and 43 with one phase of the alternator 11, in this instance, the phase represented by the alternator terminals 16b and 16c. For this purpose the alternating current terminal 42 of the field rectifier 37 is connected with the alternator terminal 16b by a conductor 44 and the alternating current terminal 43 of the field rectifier 37 is connected with the alternator terminal 16c through conductor means 45 and through the saturable core reactor 38 which will now be further described.

The saturable core reactor 38 comprises a laminated magnet frame or core 46 which, in this instance, has three parallel magnetic circuit legs 46a, 46b and 46c. The end legs 46a and 46c carry alternating current magnet coils 47 and 48 which are connected in series relation to each other in the alternating current portion of the field circuit by the conductor means 45. The intermediate leg 46b of the reactor 38 carries a direct current energizing or control winding 49 to which energizing current is supplied under the control of the voltage and current regulators 35 and 36, as will be presently explained. When the control winding 49 is energized by direct current, it produces a magnetic circuit in the core 46 of the reactor 38 which opposes and controls the magnetic flux produced by the alternating current coils 47 and 48 of the field circuit such that these alternating current coils constitute impedance coils which will, in turn, control the amount of the alternating current being supplied to the field rectifier 37 in accordance with the extent of magnetization of the reactor core 46 by the control winding 49.

The voltage regulator 35 comprises a magnet frame 51 including a core 52 having a pair of magnet coils 53 and 54 thereon, and a movable armature 55 in cooperating relation to the frame and core. The voltage regulator 35 also includes a pair of stationary and movable switch contacts 56 and 57, of which the latter is carried by the vibratory armature 55. A tension spring 58 acting on the armature 55 normally urges the movable contact 57 toward a closed position in engagement with the stationary contact 56. The coil 53 of the voltage regulator 35 is a voltage coil which is connected across the load conductors 18a and 18b by the conductors 59 and 60 and therefore responds directly to the operating condition of the alternator 11 and senses the voltage thereof. A ballast resistor 61 may be included in the energizing circuit for the magnet coil 53. The magnet coil 53 is a so-called secondary coil which is in additive relation to the voltage coil 53 and is adapted to be energized from the load conductors 18a and 18b through a circuit which is controlled by the regulator contacts and will be presently traced.

The current regulator or load limitor 36 comprises a magnet frame 62 including a core 63 carrying a load circuit series coil 64 and a vibratory armature 65 in cooperating relation to the

magnet frame and core. The current regulator 36 also includes stationary and movable switch contacts 66 and 67, of which the latter contact is carried by the vibratory armature 65 and is normally urged toward a closed position in engagement with the stationary contact by a tension spring 68.

The voltage and current regulators 35 and 36 are automatically responsive to the operating condition of the alternator 11, as mentioned above, and control the excitation of the field winding 15 by controlling the energization of the control winding 49 of the saturable reactor 38. In this way the contacts of regulators 35 and 36, by controlling relatively small quantities of electrical energy which produce changes in the magnetization of the control coil 49, are able to control much larger amounts of alternating current in the field circuit windings 47 and 48 of the saturable reactor and thus produce a strong regulating action on the excitation of the field winding 15 without subjecting the regulator contacts to harmful arcing. For this purpose the vibratory contact of the voltage and current regulators 35 and 36 are connected with the control winding 49 of the reactor 38 through circuit connections which will now be described and which include a so-called point resistor 69 and a voltage divider 70.

The voltage divider 70 comprises a resistor 70a, which is connected across the direct current load conductors 18a and 18b by the conductors 71 and 72, and a contact arm 70b which is manually shiftable along the resistor 70a. The point resistor 69 has one end thereof connected with the stationary contact 66 of the current regulator 36 by a conductor 73 and has its other end connected with the armature 55, and hence the movable contact 57, of the voltage regulator 35 by the conductor means 74. Such other end of the point resistor 69 is also connected with one end of the magnet coil 54 of the voltage regulator by the conductor means 75 and with one end of the control winding 49 of the saturable reactor 38 by the conductor 76. The other end of the magnet coil 54 of the voltage regulator is connected with the arm 70b of the voltage divider 70 by a conductor 77 and the other end of the control coil 49 of the saturable reactor is also connected with the movable arm of the voltage divider through a conductor 78. The stationary contact 56 of the voltage regulator is connected with the armature 65 of the current regulator by the conductor 79. The energizing circuit for the magnet coil 54 of the voltage regulator may also include a resistor 80 of suitable value.

In the circuit arrangement just described for the magnet coil 54 of the voltage regulator 35 and for the control winding 49 of the saturable reactor 38, the connections are such that the coil 54 and the winding 49 are energized in parallel relation to each other from the load conductors 18a and 18b through the voltage divider 70. This energizing circuit for the winding 49 of the saturable reactor and the magnet coil 54 of the voltage regulator also includes the point resistor 69 whenever the switch contacts of either the voltage regulator 35 or the current regulator 36 are open. When the point resistor 69 is inserted into the energizing circuit for the control winding 49 and the magnet coil 54 by the opening of the voltage regulator or the current regulator contacts, it will produce a decreased energization of such winding and magnet coil to thereby decrease the magnetization of the core

46 of the saturable reactor and the magnetization of the frame 51 and the core 52 of the voltage regulator.

The effect of this decrease in the magnetization of the core 46 of the saturable reactor 38 is to cause a decrease in the excitation of the field winding 15 and to permit closing of the contacts 56 and 57 of the voltage regulator. When the point resistor 69 is short-circuited out of this control circuit by the closing of the contacts of the voltage and current regulators, the energization of the control winding 49 of the saturable reactor 38 is increased and the energization of the magnet coil 54 of the voltage regulator 35 is also increased. This increase in the energization of the control winding 49 and the magnet coil 54 causes an increase in the energization of the field winding 15 and an increased pull on the armature 55 of the voltage regulator to cause opening of the contacts 56 and 57 to thereby reinsert the point resistor 69 in the control circuit. It will be understood, of course, that the opening and closing of the switch contacts of the voltage and current regulators takes place at a very rapid vibratory action.

In the circuit arrangements and functioning above described, the voltage divider 70 serves an important purpose because by selecting a setting for the contact arm 70b such that the voltage applied to the regulator contacts 56, 57 and 66, 67 will be low, harmful sparking or a sustained ionization at these contacts will be prevented.

Fig. 2 of the drawings shows an improved generating system 82 which is generally similar to the above described generating system 10 and functions in a similar manner but in which the voltage regulator 35 is a double contact regulator. Since the various parts of the system 82 are similar to the parts of the system 10 and function in a similar manner, the corresponding parts have been designated by the same reference characters, with the exception of the additional pair of contacts of the voltage regulator 35. These additional contacts of the voltage regulator are a lower pair of contacts comprising a stationary contact 83 and a movable contact 84 carried by the vibratory armature 55. The stationary contact 83 is connected with the movable contact arm 70b of the voltage divider 70 by the conductor 85.

Since the generating system 82 employs circuits similar to those described above for the system 10, and produces an effective regulation of the excitation of the alternator 11 in substantially the same way and with minimum destructive sparking at the contacts of the voltage and current regulators 35 and 36, it is not necessary to repeat the detailed description of these circuits and the functioning of the apparatus.

With respect to the lower pair of switch contacts 83 and 84 of the voltage regulator 35, additional detailed description is needed and it is accordingly pointed out that when the condition of operation of the alternator 11 is such that the functioning of the voltage regulator shifts from operation on the upper pair of contacts 56 and 57 to operation on the lower pair of contacts 83 and 84, the closing of the lower contacts will establish a circuit which substantially short-circuits the control windings 49 of the saturable reactor 38 and the magnet coil 54 of the voltage regulator and, hence, will quickly reduce the energization of this control winding and this regulator coil substantially to a zero value. This

circuit, established by the closing of the lower pair of contacts 83 and 84 and which substantially short circuits the control winding 49 and the magnet coil 54, extends from the load conductor 18a through the conductor 71, then through the left-hand portion of the resistor 70a of the voltage divider 70, through the contact arm 70b, through the conductor 85, through the lower pair of regulator contacts 83 and 84, the conductor means 74, and then through the point resistor 69 and the conductor 73 to the load conductor 18b.

By selecting a setting for the contact arm 70b of the voltage divider 70 such that the voltage applied to the contacts 83, 84 of the double contact regulator 35 will be at or below the critical value for sustained ionization, the danger of burning or welding together of the contacts by the occurrence of a high short-circuiting current when the regulator operates on the lower pair of contacts is definitely prevented.

Figs. 3 and 4 of the drawings show other generating systems 87 and 88 which are generally similar to the systems 10 and 82, respectively, but in which the saturable reactor means of the alternator field excitation circuit is a three-phase saturable reactor. In other respects, the systems 87 and 88 employ substantially the same circuits and function in substantially the same manner as the above described systems 10 and 82, and the corresponding parts and circuit connections are designated by corresponding reference characters and without repetition of the detailed description. With respect to the saturable reactor means of the generating systems 87 and 88, it is explained that the three-phase saturable reactor 89 shown in each of these systems comprises three individual saturable reactors 89a, 89b and 89c, each of which is substantially identical with the saturable reactor 38 of the generating system 10 described above. The three individual reactors 89a, 89b and 89c are located in the alternating current circuit portions of the energizing circuit for the alternator field 15 and one of these individual reactors is located in each of the three-phase alternating current circuit portions 90, 91 and 92 which connect the alternating current terminals 93, 94 and 95 of the field rectifier 37 with the alternating current terminals 16a, 16b and 16c of the alternator.

From the accompanying drawings and the foregoing detailed description it will now be readily understood that this invention provides generating system control means by which the field excitation of a variable speed variable load alternator can be effectively and reliably controlled by the use of a voltage regulating device of the relay type acting through a saturable reactor located in the alternating current portion of the field energizing circuit. It will also be seen that the control exercised on the field circuit and the saturable reactor means contained therein can be produced, in part, by a voltage regulator and, in part, by a current regulator and also that, if desired, the voltage regulator can be of the double contact type and the saturable core reactor means can be a three-phase reactor. It will now also be recognized that since the regulating action of the voltage and current regulators on the field excitation of the alternator, when accomplished through the saturable reactor means, requires only relatively small voltage and current values to be imposed on the vibratory contacts of the regulators and, hence, these contacts will have a long service life. Additionally, it will be seen

that this invention provides load relay energizing means for a vehicle generating system of this character in which the magnet coil of the load relay is energized directly from the alternator through an auxiliary rectifier.

Although the generating system control apparatus of this invention has been illustrated and described herein to a somewhat detailed extent, it will be understood, of course, that the invention is not to be regarded as being limited correspondingly in scope but includes all changes and modifications coming within the terms of the claims hereof.

Having thus described my invention, I claim:

1. In an electrical generating system for use on motor vehicles, an alternator having a field winding, a main rectifier, an external direct current load circuit connected with said alternator through said main rectifier, a field circuit connected with said alternator and including an auxiliary rectifier for supplying rectified current to said field winding, a saturable reactor comprising a core having thereon a magnetizing coil and an impedance coil, said impedance coil being located in the alternating current portion of said field circuit, a voltage regulator of the relay type having magnet coil means responsive to the operation of said alternator and also having vibratory switch contact means, a circuit for energization of said magnet coil means and said magnetizing coil from said direct current load circuit and controlled by said contact means, and a voltage divider in the last-mentioned circuit for selecting the voltage of the current supplied to said magnet coil means.

2. In an electrical generating system for use on motor vehicles, an alternator having a field winding, a main rectifier, an external direct current load circuit connected with said alternator through said main rectifier, a field circuit connected with said alternator and including an auxiliary rectifier for supplying rectified current to said field winding, a saturable reactor comprising a core having thereon a magnetizing coil and an impedance coil, said impedance coil being located in the alternating current portion of said field circuit, a voltage regulator of the relay type having magnet coil means responsive to the operation of said alternator and also having vibratory switch contact means and a resistor in shunt relation to said contact means, a circuit for energization of said magnet coil means and said magnetizing coil from said direct current load circuit and controlled by said contact means and said resistor, and a voltage divider in the last-mentioned circuit adapted to permit the selection of a relatively low value for the voltage applied to said contact means.

3. In an electrical generating system for use on motor vehicles, an alternator having a field winding, a main rectifier, an external direct current load circuit connected with said alternator through said main rectifier, a field circuit connected with said alternator and including an auxiliary rectifier for supplying rectified current to said field winding, a saturable reactor comprising a core having thereon a magnetizing coil and an impedance coil, said impedance coil being located in the alternating current portion of said field circuit, a voltage regulator of the relay type having a first magnet coil connected across said direct current load circuit and a second magnet coil and also having vibratory switch contact means, and a circuit for energization of said magnetizing coil and said second magnet coil from

said direct current load circuit and controlled by said contact means.

4. In an electrical generating system for use on motor vehicles, an alternator having a field winding, a main rectifier, an external direct current load circuit connected with said alternator through said main rectifier, a field circuit connected with said alternator and including an auxiliary rectifier for supplying rectified current to said field winding, a saturable reactor comprising a core having thereon a magnetizing coil and an impedance coil, said impedance coil being located in the alternating current portion of said field circuit, a voltage regulator of the relay type having a first magnet coil connected across said direct current load circuit and a second magnet coil and also having vibratory switch contact means, a circuit for energization of said magnetizing coil and said second magnet coil from said direct current load circuit and controlled by said contact means, and a voltage divider in the last-mentioned circuit for varying the voltage of the current supplied to said magnetizing coil and to said second magnet coil and also adapted to permit the selection of a relatively low value for the voltage applied to said contact means.

5. In an electrical generating system for use on motor vehicles, an alternator having a field winding, a main rectifier, an external direct current load circuit connected with said alternator through said main rectifier, a field circuit connected with said alternator and including an auxiliary rectifier for supplying rectified current to said field winding, a saturable reactor comprising a core having thereon a magnetizing coil and an impedance coil, said impedance coil being located in the alternating current portion of said field circuit, a voltage regulator of the relay type having voltage magnet coil means connected across said direct current load circuit and responsive to the operation of said alternator, said voltage regulator also comprising switch contact means adapted to be vibrated by said voltage magnet coil means, a current regulator of the relay type having a current magnet coil in said direct current load circuit and responsive to the operation of said alternator and switch contact means adapted to be vibrated by said current magnet coil, and a circuit for energizing said magnetizing coil from said direct current load circuit and controlled by the switch contact means of said voltage regulator and the switch contact means of said current regulator.

6. In an electrical generating system for use on motor vehicles, an alternator having a field winding, a main rectifier, an external direct current load circuit connected with said alternator through said main rectifier, a field circuit connected with said alternator and including an auxiliary rectifier for supplying rectified current to said field winding, a saturable reactor comprising a core having thereon a magnetizing coil and an impedance coil, said impedance coil being located in the alternating current portion of said field circuit, a voltage regulator of the relay type having magnet coil means responsive to the operation of said alternator and switch contact means adapted to be vibrated by said magnet coil means, a current regulator of the relay type having a current magnet coil in said load circuit and responsive to the operation of said alternator and switch contact means adapted to be vibrated by said current magnet coil, a circuit for energizing said magnet coil means of said voltage regulator and said magnetizing coil from said direct cur-

rent load circuit and controlled by the switch contact means of said voltage regulator and by the switch contact means of said current regulator, and a voltage divider in the last-mentioned circuit for varying the voltage of the current supplied to said magnet coil means and also adapted to permit the selection of a relatively low value for the voltage applied to said contact means.

7. In an electrical generating system for use on motor vehicles, an alternator having a field winding and load terminals, a main rectifier, an external direct current load circuit connected with said load terminals through said main rectifier, a load relay having a magnet coil and series switch contacts controlling said load circuit, said switch contacts being normally open and adapted to be closed by energization of said magnet coil, regulating means including relay means energized from said load circuit and operably connected with said field winding for varying the energization of the latter automatically in response to changes in the operating conditions of said alternator, an auxiliary rectifier, and circuit means connecting said magnet coil with said load terminals through said auxiliary rectifier for causing such energization of said magnet coil and closing of said series switch contacts in response to operation of the alternator.

8. In an electrical generating system for use on motor vehicles, a three-phase alternator having a field winding and load terminals, a full wave three-phase main rectifier, an external direct current load circuit connected with said load terminals through said main rectifier, a load relay having a magnet coil and series switch contacts controlling said load circuit, said switch contacts being normally open and adapted to be closed by energization of said magnet coil, regulating means including relay means energized from said load circuit and operably connected with said field winding for varying the energization of the latter automatically in response to changes in the operating conditions of said alternator, a full wave three-phase auxiliary rectifier, and circuit means connecting said magnet coil with said load terminals through said auxiliary rectifier for causing such energization of said magnet coil and closing of said series switch contacts in response to operation of the alternator.

9. In an electrical generating system for use on motor vehicles, an alternator having a field winding, a main rectifier, an external direct current load circuit connected with said alternator through said main rectifier, a field circuit connected with said alternator and including an auxiliary rectifier for supplying rectified current to said field winding, a saturable reactor comprising a core having thereon a magnetizing coil means and an impedance coil means, said impedance coil means being located in the alternating current portion of said field circuit, a first control circuit for energizing said magnetizing coil means, a second control circuit adapted to substantially short-circuit said magnetizing coil means, and a voltage regulator of the relay type having voltage magnet coil means connected across said direct current load circuit and responsive to the operation of said alternator, said voltage regulator also comprising vibratory contact means including one pair of contacts controlling said first control circuit and a second pair of contacts controlling said second control circuit.

10. In an electrical generating system for use on motor vehicles, an alternator having a field winding, a main rectifier, an external direct cur-

11

rent load circuit connected with said alternator through said main rectifier, a field circuit connected with said alternator and including an auxiliary rectifier for supplying rectified current to said field winding, a saturable reactor comprising a core having thereon a magnetizing coil means and an impedance coil means, said impedance coil means being located in the alternating current portion of said field circuit, a first control circuit for energizing said magnetizing coil means, a second control circuit adapted to substantially short-circuit said magnetizing coil means, a voltage regulator of the relay type having voltage magnet coil means responsive to the operation of said alternator and vibratory contact means including one pair of contacts controlling said first control circuit and a second pair of contacts controlling said second control circuit, and a voltage divider connecting said control circuits with said direct current load circuit and adapted to permit the selection of a relatively low value for the voltage applied to the contact means of said voltage regulator.

11. In an electrical generating system for use on motor vehicles, a polyphase alternator having a field winding, a main rectifier, an external direct current load circuit connected with said alternator through said main rectifier, a field circuit connected with said alternator and including an auxiliary rectifier for supplying rectified current to said field winding, saturable reactors corresponding in number with the phases of said alternator and each such reactor comprising core means having magnetizing and impedance coils thereon, said impedance coils being located in the alternating current portion of said field circuit and connected with the respective phase terminals of said alternator, a first control circuit for energizing said magnetizing coils, a second control circuit adapted to substantially short-circuit said magnetizing coils, and a voltage regulator of the relay type having voltage magnet coil means connected across said direct current load circuit and responsive to the operation of said alternator, said voltage regulator also com-

5

prising vibratory contact means including one pair of contacts controlling said first control circuit and a second pair of contacts controlling said second control circuit.

12. In an electrical generating system for use on motor vehicles, a polyphase alternator having a field winding, a main rectifier, an external direct current load circuit connected with said alternator through said main rectifier, a field circuit connected with said alternator and including an auxiliary rectifier for supplying rectified current to said field winding, saturable reactors corresponding in number with the phases of said alternator and each such reactor comprising core means having magnetizing and impedance coils thereon, said impedance coils being located in the alternating current portion of said field circuit and connected with the respective phase terminals of said alternator, a first control circuit for energizing said magnetizing coils, a second control circuit adapted to substantially short-circuit said magnetizing coils, a voltage regulator of the relay type having voltage magnet coil means connected across said direct current load circuit and responsive to the operation of said alternator, said voltage regulator also comprising vibratory contact means including one pair of contacts controlling said first control circuit and a second pair of contacts controlling said second control circuit, and a voltage divider connecting said control circuits with said direct current load circuit and adapted to permit the selection of a relatively low value for the voltage applied to the contact means of said voltage regulator.
